CLAIM

The ornamental design for a pole-mountable camera support structure, as shown and described.

DESCRIPTION

FIG. 1 is a front perspective view of a pole-mountable camera support structure, showing our design;
FIG. 2 is a front view thereof;
FIG. 3 is a rear view thereof;
FIG. 4 is a side view thereof;
FIG. 5 is an opposing side view thereof;
FIG. 6 is a bottom view thereof;
FIG. 7 is a top view thereof; and,
FIG. 8 is a front perspective environmental view thereof.
The broken lines shown herein depict environmental subject matter and form no part of the claimed design. The stippling patterns shown in FIGS. 1-8 indicate components that are the same color. The color indicated by the stippling patterns may be any color that is the same for each component including the stippling patterns.
